SKATE

Dale M. Harris, Toledo, Ohio, assignor of one-half
to Jesse J. Haube, Toledo, Ohio

Application June 28, 1934, Serial No. 732,879

7 Claims. (Cl. 208—179)

This invention relates to foot base structure with features of comfort to the user of the skate.

This invention has utility when incorporated in heel and toe elements, their assembly, and runner feature mountings, especially as yieldable.

Referring to the drawing:

Fig. 1 is a side elevation of an embodiment of the invention in a roller skate;

Fig. 2 is a bottom plan view of the skate of Fig. 1;

Fig. 3 is a section on the line III—III, Fig. 2;

Fig. 4 is a section on the line IV—IV, Fig. 3;

Fig. 5 is a detail in top plan of the runner or tread portion of a single wheel type and a portion of its mounting lever therefrom;

Fig. 6 is a plan of the toe portion or section blank of the skate structure;

Fig. 7 is a fragmentary plan view of the blank for the heel portion of the skate structure;

Fig. 8 is a plan view of a blank connecting plate between the heel and toe sections; and

Fig. 9 is a section through a cushioning or buffer limit for lever movement having the bolt or holding pin extending lengthwise of the lever.

Toe section 1 of the foot portion of the blank is shown provided with ears 2, and bolt hole 3. Longitudinally of the extent of this toe section 1 there is downwardly extending rib 4. From this rib 4, by weld assembly, there extends depending

fork 5 astride reduced intermediate section 6 of oppositely threaded screw 7. The toe portion 1 additionally has headed rivets 8 extending through slots 9 of sole clips 10, transversely adjustable as key or wrench is applied to squared terminus 11 of this screw 7 to adjust the sole-engaging clips into and out of shoe sole gripping position. The depending ears 2 mount rivets 12 providing a swivel connection as a fulcrum for lever having depending arm portions 13 and

therefrom, forwardly inclined arm portions 14 terminating in eye portions 15 mounting transverse bolt 16 as a carrier for runner roller or rollers 17. The single roller may be mounted between the arms 14 (Fig. 5) while for a double roller, the free ends beyond the arms mount rollers 17.

The lever portion 14 has drop intermediate seat 18 opposing bracket 19 fixed with the toe portion 1. This bracket 19 has seat 20. Between these seats 18, 20, there may be cushion means or rubber buffer 21. This will effectively limit and cushion the movement of the roller or rollers toward the toe piece 1. Bolt 22 centrally of this buffer 21 and coacting between the member 19 and the seat 18 may be adjustable for the degree of

compression to initially be upon the cushion pad 21 and also limit the movement of the lever 13, 14, away from the toe piece 1. About this bolt 22 is sleeve 23, desirably of less length than the adjustment for the buffer 21. There is thus provided a limit in the compression of the buffer 21 to preclude striking of the rollers 17 against the under side of the toe piece 1.

Intermediate plate 24 is shown provided with marginal flanges 25 and intermediate groove 26 10 complementary with the rib 4 and thereby providing a rib and groove or tongue and groove slide guide cooperation longitudinally of the skate, definitely holding the toe piece 1 against angular shifting relatively to the intermediate or connector plate 24. Slot 27 in this plate 24 may have bolt 28 therethrough and through the opening 3 in the piece 1 serve as the locking means for the adjusting extension of this roller skate. This locking bolt 28 is in the region of the fulcrum 20 pivot 12 for the lever and thereby provides a simple, substantial mounting for this cushioning runner or tread.

Heel portion or section 29 has ears 2 and opening 3 analogous to such portions in the toe section 1. Additionally, this heel has longitudinally thereof a downwardly-depressed rib 30 cooperating with the groove 26 of the connector plate 24. Slot 31 in the connector plate 24 is engaged by bolt 28 through opening 3 in the heel section 29. 30 Adjustable reversely extending lever 13, 14, carries runner roller or rollers 17 for the heel portion of the socket. There is similar buffer here, while the roller for the heel extends a distance to have its axis close to the rear edge of the heel 35 of the one having the skate. This heel of the skater is retained in the section 29 by upwardly extending flange portions 32 having openings 33 for hold strap 34.

The buffer as shown in Fig. 3 has direct compression with a degree of stability against side tilting. This is desirable with a pair of the runner rollers 17 at the ends of the respective levers.

In the instance a single roller is used between the arms 14 of the lever, there may be additional 45 comfort to the skater due to slight transverse cushioning. In such instance, the lever portion 14 may have its cup portion 18 with ears 35 mounting bolt 36 extending through cushioning member 37, and slots 38 in flanges 39 from the bracket 19 (Fig. 9). 50 This rubber cushion or buffer 37 serves to resist yieldingly compression or movement of the wheel or roller toward the foot of the wearer of the skate as a stroke is taken or as there be an unevenness in the surface over which skating occurs. 55

This is as with the buffer of Fig. 3. Also, there is a limit to the movement of the roller away from the foot of the wearer of the skate, due to the slots 38 in the ears 39. However, additionally, 8 there may be slight transverse rocking or weave on the bolt 36 as an axis permitted by the sheet metal structure of the levers 13, 14.

The skate is accordingly a device which may be built of light weight in sheet metal of slight gage. 10 Still there is strength and toughness substantial to withstand rough usage given by youth or children, with hold up qualities and ease for the user in taking up harsh impacts. Further, the skate is readily adaptable to a range of foot sizes 15 with retention of proper relation between the support or rollers and the foot of the wearer.

What is claimed and it is desired to secure by Letters Patent is:

1. A skate embodying a base as a foot support 20 providing heel and toe sections, a lever having a swivel mounting confined to straight line swing to and from said base intermediate the heel and toe portions, said lever extending outwardly therefrom toward one of said sections to provide a free 25 end, a roller mounted on said free end, and yieldable means between said base and lever.

2. A skate base providing heel and toe portions 30 with an intermediate region therebetween, a lever pivotally secured to said skate adjacent the intermediate region and extending forwardly therefrom to terminate in a free end below the toe portion, a roller mounted on said free end, and cushioning means for the lever between said lever and base engaging the lever intermediate its length.

35 3. A skate base providing heel and toe portions with an intermediate region therebetween, a lever pivotally secured to said skate adjacent the intermediate region and extending therefrom to terminate in a free end below said heel portion, a

roller mounted on said free end, and cushioning means for the lever between said lever and base engaging the lever intermediate its length.

4. A skate base providing heel and toe portions with an intermediate region therebetween, levers 5 pivotally secured to the intermediate region extending in opposite directions therefrom to terminate in free ends below said heel and toe portions, a roller mounted on the free end of each lever, and cushioning means between each lever 10 and the base, said cushioning means engaging the lever intermediate its length.

5. A skate embodying a base providing a heel and toe portion, an intermediate region therebetween, a lever pivotally secured to said skate adjacent said intermediate region and extending therefrom toward one end of the base to terminate in a free end therebelow, a roller mounted on said free end, a seat in said lever intermediate its length, and a buffer on said lever between the 20 roller and free end and between said seat and base.

6. A roller skate embodying a foot supporting plate, a portion of said plate turned downwardly to provide an arm, a lever pivotally connected to 25 said arm for movement of its free end to and from said plate, a roller mounted on the free end, and cushioning means between the plate and lever intermediate its length.

7. A roller skate embodying a foot supporting 30 plate, portions of said plate in the intermediate foot region turned downwardly to provide a pair of parallel arms, an H-shaped lever pivotally connected to said arms to have its free end confined to movement to and from said plate, and a buffer between said plate and the cross arm of said H-shaped lever.

DALE M. HARRIS.
